UNITED STATES PATENT OFFICE.

CHARLES C. JAMES, OF NEW YORK, AND GEORGE C. JAMES, OF YONKERS, NEW YORK.

DISPLAY APPARATUS.

1,375,005.

Specification of Letters Patent. Patented Apr. 19, 1921.

Application filed May 8, 1920. Serial No. 379,697.

To all whom it may concern:

Be it known that we, CHARLES C. JAMES and GEORGE C. JAMES, both citizens of the United States, and residents, respectively, 5 of the borough of Manhattan, county and State of New York, and of Yonkers, county of Westchester, and State of New York, have invented certain new and useful Improvements in Display Apparatus, of which

10 the following is a specification.

The invention relates to improvements in display apparatus, and while it may be used for display purposes of many kinds, it is particularly directed to apparatus for displaying consecutively a series of advertisements or announcements such for example as the station stops of a train, or the various vaudeville acts on a theatrical stage.

The invention is herein shown and described as embodied in a display machine of the traveling web type, and in which the web carrying the signs is wound back and forth from one roller to another. In machines of this type, as the web is rolled back and forth from one roller onto the other, naturally the rollers are operating with different effective diameters. The one having the greatest amount of the web or sheet on it will per revolution take up or roll off a greater amount of the sheet than the one having the less amount. Therefore in order to avoid slack in the sheet it is important to drive but one of the rollers, allowing the other to follow due to the pull of the sheet, 30 and to provide means whereby this can be done with but one driving motor. It is also important in display machines to arrest the web or other means for carrying the display signs at certain predetermined positions

35 40 with respect to the display window, and therefore it is important to provide some means that will insure the web being so arrested when the driving power is cut off or disconnected; and it is important to accomplish this with relatively light mechanism to reduce weight and cost, and to accomplish it without positively and abruptly arresting the rotation of the motor and connecting gearing so as not to subject these 45 50 parts to undue strain due to stopping them suddenly under their momentum. By this invention it is endeavored to accomplish these desired features.

The main object of the invention is to provide 55 an apparatus which is both simple and efficient in operation and construction. A

further object of the invention is to provide an apparatus in which the display means are operated intermittently and are not likely to overrun the display position. A further 60 object of the invention is to provide a new arrangement for automatically causing the display means to stop at predetermined points. A further object of the invention is to provide an arrangement by which such 65 display means may be moved back and forth and operated in both directions by the same motor in an improved manner. Further and more specific objects, features and advantages will more clearly appear 70 from the detailed description given below taken in connection with the accompanying drawings which form a part of this specification.

The invention consists in the novel features, arrangements and combination of parts hereinafter shown and described, and the invention is more particularly pointed out in the appended claims.

In the drawings, Figure 1 is a front view 80 of the apparatus embodying our improvements in one form, part of the same being broken away to more clearly illustrate certain of the parts;

Fig. 2 is a view of the left-hand end of 85 the apparatus as viewed in Fig. 1;

Fig. 3 is a section taken on the line 3—3 of Fig. 1;

Fig. 4 is a vertical section of the driving connections shown in Fig. 1; 90

Fig. 5 is a diagram illustrating the electrical connections;

Fig. 6 is a front view of a portion of the apparatus illustrating a modification; and

Fig. 7 is an end view of the arrangement 95 shown in Fig. 6.

Referring to Figs. 1 to 4, inclusive, 8 represents a suitable frame in which are rotatably mounted two rolls 9 and 10, rigidly secured to suitable shafts 11 and 12, respectively. 13 represents a display sheet on which the announcements or advertising matter to be displayed are printed or otherwise affixed. 14 represents an electric motor adapted, by means of a worm, to drive 105 a worm gear 15 keyed on a driving shaft 16. The worm gear 15 is adapted to drive the shaft 16, but the shaft 16 is adapted to have longitudinal movement therethrough. Fixed to the driving shaft 16 are two clutch 110 members 18 and 19 adapted to coöperate respectively with ratchet clutch faces on

sprocket wheels 20 and 21 loosely mounted upon said shaft. A sprocket chain 22 operatively connects the sprocket wheel 20 with a sprocket wheel 23 mounted to rotate on the shaft 12. The sprocket 23 abuts a collar 24 fixed on the shaft 12 and is held thereagainst by means of a spring 25, one end of which abuts a collar 26 fixed on the shaft 12 and the other end of which 10 presses against a collar 27 slidably keyed to shaft 12 and engaging a friction disk 28 to press it toward the sprocket 23 so that when the sprocket wheel 23 is turned it will, through this yieldable or friction driving connection, drive the shaft 12 and the roll 10 secured thereto.

The sprocket wheel 21 is likewise adapted to drive a sprocket chain 29 driving a sprocket 30 mounted to rotate on the shaft 20 11 and abutting a collar 31 fixed to the shaft 11. A spring 32, one end of which abuts a collar 33 fixed on the shaft 11, and the other end of which abuts a collar 34 slidably keyed on the shaft 11 forces the collar 34 and friction disk 35 toward and against the sprocket 30 so that upon driving the sprocket 29 and sprocket wheel 30 the latter will, through this yieldable or frictional driving connection, drive the shaft 11 25 and with it the roll 9 secured thereon. When the motor is rotated in one direction the cam face on clutch 18 will be forced into operative engagement with the cam face on sprocket 20 by reason of the cam face on clutch 19 riding over and up upon the co-operating face of sprocket 21 forcing the shaft 16 to the left as viewed in Fig. 4 so that the clutch 18 will be brought into driving engagement with the sprocket 20. Likewise when the motor is rotated in the opposite direction the cam face on clutch member 18 will ride up upon the co-operating face of sprocket 21 and force the shaft 16 to the right as viewed in Fig. 4, causing 40 the clutch 19 to be forced into operative driving engagement with the sprocket 21. 45

Thus when the motor is energized so as to rotate in one direction it will drive the roll 10 to wind up the sheet 13 thereon, the roll 9 being free to unwind the sheet 13 therefrom, and when the motor 14 is energized to rotate in the opposite direction it will drive the roll 9 to wind up the sheet 13 thereon and leave the roll 10 free to unwind 55 the sheet therefrom.

In order that when the motor is deenergized the momentum of the rotating parts will not cause a continued rotation of either roll 9 or 10, means are provided for positively stopping the rotation of the rolls 9 or 10. For this purpose there is secured to the shaft 11 a toothed wheel 38 and to the shaft 12 a toothed wheel 39, each having a number of closely and uniformly 60 spaced teeth as shown in the drawings.

40 represents a rocker arm suitably pivoted to the framework, to one end of which arm is connected a rod 41 at the upper end of which is carried a finger or tooth 42 sliding in a fixed guide member 43 and adapted to engage the teeth of the wheel 38. On the other side a rod 44 is connected to the rocker arm 40 and at the lower end of the rod 44 is a tooth 45 sliding in a fixed guide member 46 and adapted to engage the teeth of wheel 39. 70 The rocker arm 40 also carries an armature 47 adapted to be attracted by an electromagnet 48 comprising two magnet coils 49 and 50. A spring 51 normally pulls the armature 47 away from the magnet 48 causing the rocker arm 40 to operate the links 41 and 44 so as to force the teeth 42 and 45 into engagement with the teeth of wheels 38 and 39 to positively prevent rotation of the rolls 9 and 10. Due to the relatively 85 large number of uniformly spaced teeth of the wheels 38 and 39, the rolls are instantly stopped when the magnet is deenergized, to throw the teeth or fingers 42 and 45 into engagement with their corresponding wheels 90 so that the web is promptly arrested upon the deenergization of the motor circuit controlled as hereinafter described, thus preventing "overrunning." This "overrunning" is a serious objection in continuous 95 web machines, due to the fact that the error or "overrunning" is cumulative for each operation of the machine so that if there is only an "overrunning" of a fraction of an inch for each movement, after 100 a series of movements the signs may be so far out of register with the window as to partly conceal the sign. At the same time that the motor is energized to drive either of the rolls 9 or 10, the magnet coils 49 and 105 50 are energized causing the armature 47 to be attracted thereto and the rocker arm 40 to be oscillated to withdraw the teeth 42 and 45 from engagement with the wheels 38 and 39, permitting the rolls 9 and 10 to 110 be operated to wind up the sheet 13 on one and unwind it from the other.

When the motor is deenergized and the rolls arrested, the friction clutches on shafts 11 and 12 permit the motor and connecting gearing to continue to rotate under their momentum so as to more gradually come to a stop without jarring or straining these parts.

In order that the motor may be deenergized and the movement of the sheet 13 automatically stopped when it has reached display position, means are provided for deenergizing the motor responsive to the movements of the sheet. For this purpose 125 the sheet is provided with suitable vertical slots directly opposite that portion of the sheet to be displayed. Co-operating with these slots in the sheet 13 is a finger 52 pivoted at 53 and normally retained in the po- 130

sition shown in full lines in Fig. 3 by tension spring 54. Integral with the finger 52 on the opposite side of the pivot 53 is a cam 55 coöperating with a resilient or spring switch member 56 adapted to be pressed into contact with an electrical contact 57 in the motor circuit. The upper end of the spring member 56 is rigidly secured to electrical contact 58. In front of the sheet 13 there is arranged a thin plate 59 provided with a slot 60. When a slot within the sheet 13 arrives opposite the slot 60 the finger 52 will be permitted to extend through the slot in the sheet 13 and assume the position shown in full lines in Fig. 3. In this position the spring 56 moves away from the contact 57 thus electrically disconnecting the contacts 57 and 58. When the sheet moves either upward or downward the end of the slot in the sheet 13 will strike the finger 52 causing it to be rotated, as for example, as shown in dotted lines in Fig. 3 thereby causing the cam 55 to force the spring switch 56 into engagement with the contact 57. The cam 58 will hold the spring switch 56 in engagement with contact 57 until another slot in the sheet 13 arrives opposite the slot 60 whereupon the finger 52 will be permitted to resume the position shown in full lines in Fig. 3 under the action of spring 54.

Referring to Fig. 5 the armature of the motor 14 is there indicated at 60 and its field at 61. Current from any suitable source is supplied to the motor through the conductors 62 and 63. 64 represents a hand operated push button switch which is normally maintained open and only closed when pushed by the hand. At 65 is shown a double throw switch adapted to suitably connect contacts 66, 67 and 68 and contacts 69, 70 and 71. That is, when the switch 65 is thrown in one direction it will connect contact 67 with contact 68 and contact 70 with contact 69 as shown in dotted lines, and when the switch is thrown in the other direction it will connect contact 67 with contact 66 and contact 70 with contact 71. Assuming the switch 65 to be thrown in the position indicated by dotted lines in Fig. 5, then if the hand-operated switch 64 be closed current will flow through the conductor 62 magnet coil 49 switch 64, motor armature 60, magnet coil 50 to contacts 67 and 68, through motor field 61 to contact 66, and thence to contact 69 and 70 and assuming the hand switch 72 to be closed, out through the conductor 63. This will cause the motor to be energized and likewise the magnet coils 49 and 50 to be energized so that the locking teeth 42 and 45 will be withdrawn and the motor will cause the sheet 13 to be wound up upon one roll and unwound from the other. Immediately however, the sheet 13 has moved very slightly the end of the slot in the sheet will cause the finger 52 to rotate and close the spring switch 56 thereby directly connecting contacts 57 and 58 so that the push button switch 54 may then be released and the motor will continue to be energized, but will be automatically deenergized when another slot in the sheet 13 comes opposite the finger 52 permitting the spring 54 to move the finger 52 and cause the spring switch 56 to be opened. Such deenergization of the motor will ordinarily take place when another display on the sheet 13 has reached proper display position. At the same time that the motor is thus deenergized automatically by means of the finger 52 and spring switch 56, the magnets 49 and 50 will be deenergized and the spring 51 will cause the rocker arm 40 to force the teeth 42 and 45 into engagement with the teeth of wheels 38 and 39 thereby positively preventing further rotation of the rolls 9 and 10, although the motor, due to the momentum of its rotating parts, may continue to rotate the driving sprockets 23 and 30 which will slide in contact with the means frictionally engaging the same, which frictional means will serve as a brake for the motor. Thus by having the motor drive the rolls 9 and 10 through yieldably or frictional driving connections the rolls 9 and 10 may be immediately stopped by means of the positive locking means 42 and 45 without injury to the motor and driving connections by reason of their momenta. If it is desired to move the sheet in the opposite direction the double throw switch 65 is thrown to connect the contact 67 with contact 66 and contact 70 with contact 71 whereby the current in the field 61 will be reversed causing the motor to rotate in the opposite direction upon closing switch 64 and assuming the motor to have been driving the roll 10 will cause the driving member 16 to be rotated in the opposite direction whereby the clutch member 18 will be forced out of engagement with the sprocket 20 and the clutch 19 will be forced into driving engagement with the sprocket 21 so that the motor will drive the roll 9 through its yieldable or frictional driving connection.

Referring to Figs. 6 and 7, I there show a modified arrangement for positively stopping the rotation of the rolls 9 and 10. In this modification instead of the brake magnets 49 and 50, the motor shaft is extended as at 70 and carries a ball governor 71, one end of which is rigidly secured to the shaft 70 at 72 and the other end of which is provided with a grooved member 73 slidable on the shaft 70. Engaging the groove in member 73 is one end of a rocker arm 74 pivoted at 75. The other end of the rocker arm is pivotally connected to a link 75 the upper end of which is pivotally connected to one end of a rocker arm 76 pivoted on

the axis of shaft 16. The rocker arm 76 also has connected to it a link 77 carrying at its upper end a tooth 78 sliding in a guide 79 and adapted to engage the teeth 5 of a toothed wheel 80 rigidly secured to the shaft 11 which carries the roll 9. The rocker arm 76 also has pivoted to it a link 81 carrying at its lower end a tooth 82 sliding in a guide 83 and adapted to engage 10 the teeth of the tooth wheel 84 rigidly secured to the shaft 12 which drives the roll 10. When the motor is energized it soon reaches a speed where the ball governor 71 will cause the grooved member 73 to be 15 pulled upwardly as viewed in Fig. 7, along the shaft 70, causing a rocker arm 74 to be oscillated and with it the rocker arm 76 which, through link 77, pulls teeth 28 out 20 of engagement with the wheel 80 and through link 81, pulls tooth 82 out of engagement with the wheel 84. By reason of the above the devices which normally lock the rolls 9 and 10 against rotation are withdrawn so as to permit rotation of the rolls 25 promptly after the motor 14 is energized. When the motor 14 is deenergized the collapsing of the ball governor 71 causes the rocker arm 24 to be operated in the opposite direction and a very slight movement 30 in such direction causes the teeth 78 and 82 to engage the toothed wheels 80 and 84, thereby positively preventing further movement of the rolls 9 and 10, although, as above explained, the motor, because of its 35 momentum, may continue to rotate so as to gradually come to a stop by reason of the slipping of the frictional driving connections.

The motor in this modification must have 40 sufficient torque to be able to start up under the load of the friction clutch. While this modification will suffice for certain classes of work, it is not so accurate in stopping the web at definite points as is the first 45 device, due to the time element of the governor which must not be set too delicately on some commercial electric circuits.

Although we have described our improvements in great detail and with respect to 50 certain preferred forms, we do not desire to be limited to such details or forms since many changes and modifications may be made and the invention embodied in widely different forms without departing from the spirit and scope thereof in its broader aspects.

What we claim as new and desire to secure by Letters Patent, is:

1. A display apparatus having in combination two rolls, a display sheet adapted to be wound upon and unwound from said rolls respectively, a motor for driving both rolls, a yieldable driving connection between each roll and the motor, clutches for connecting the motor with said yieldable driv-

ing connections respectively for driving one roll or the other, and positively acting stopping means acting positively on the roll side of the yieldable driving connections for positively stopping the rotation of the rolls 70 responsive to the deenergization of the motor without undue shock on the motor parts.

2. A display apparatus having in combination two rolls, a display sheet adapted 75 to be wound upon and unwound from said rolls respectively, a motor for driving both rolls, a yieldable driving connection between each roll and the motor, clutches for connecting the motor with said yieldable 80 driving connections respectively for driving one roll or the other, whereby when one roll is being driven by the motor the other is free to follow due to the pull of the sheet and vice versa, means operatively connected with 85 the rolls on the roll side of the yieldable driving connections for suddenly and definitely stopping the movement of the sheet when the driving power is cut off without undue shock on the motor parts, a switch 90 for starting the motor, and means controlled responsive to the movements of the sheet for maintaining the energization of the motor for a predetermined movement of the sheet and for then automatically cutting 95 off the driving power.

3. A display apparatus having in combination two rolls, display means adapted to be wound upon and unwound from said rolls respectively, a motor, two clutches for 100 connecting the motor to the rolls, one for driving one roll from the motor and the other for driving the other roll from the motor, a stub shaft, the driving member of each of said clutches being mounted on said 105 stub shaft and connected to move together and rotated by the motor, the driven members of said clutches being geared respectively to the shafts of the rolls, and the engaging portions of the coöperating members 110 of each clutch being such that the driving clutch members will be automatically shifted to clutch the motor to drive one roll or the other depending upon the direction of rotation of the motor.

4. A display apparatus having in combination two rolls, a display means adapted to be wound upon and unwound from said rolls respectively, means for driving the rolls comprising a motor and a frictional driving connection, such as to permit rotation of the motor when the rotation of the roll is suddenly arrested, and means operated responsive to deenergization of the motor for positively stopping the rotation of both 120 rolls.

5. A display apparatus having in combination two rolls, a display sheet adapted to be wound upon and unwound from said rolls respectively, a motor for driving both 130

rolls, a yieldable driving connection between each roll and the motor to protect the motor from sudden stoppage of the rolls, two clutches for connecting the motor to the 5 rolls, one for driving one roll from the motor and the other for driving the other roll from the motor, said clutches being adapted to automatically clutch the motor to one roll of the other responsive to the 10 direction of rotation of the motor, and means acting upon the rolls for suddenly and definitely stopping the movement of the sheet responsive to the deenergization of the motor.

15 6. A self contained display apparatus comprising a frame, a pair of rolls rotatably supported by said frame, display means adapted to be wound upon and unwound from said rolls respectively, a shaft for each roll, a 20 driven gear on each shaft and a yieldable connection for each shaft connecting said gear and shaft, the gears and yieldable connections for each roll being on the same side of the frame, a driving motor also supported 25 from the same side of the frame and a shaft driven by said motor, two clutch members rotated by the motor, and two other clutch members adapted to be driven respectively by the first mentioned clutch members and 30 geared respectively to the driving gears on the roll shafts, one or the other of the first two mentioned clutch members being adapted to be automatically clutched with its corresponding clutch member responsive to and 35 depending upon the direction of rotation of the motor, and electromagnetically actuated arresting means with control means for same, for automatically arresting the rotation of the pulling roll at the end of each of 40 a series of predetermined movements of the display means.

7. A self contained display apparatus comprising a frame, a pair of rolls rotatably supported by said frame, display means adapted 45 to be wound upon and unwound from said rolls respectively, a shaft for each roll, a driven gear on each shaft and a yieldable connection for each shaft connecting said gear and shaft, the gears and yieldable connections for each roll being on the same side 50 of the frame, a driving motor also supported from the same side of the frame and a shaft driven by said motor, two clutch members rotated by the motor, and two other clutch 55 members adapted to be driven respectively by the first mentioned clutch members and geared respectively by the first mentioned clutch members and geared respectively to the driving gears on the roll shafts, one or 60 the other of the first two mentioned clutch members being adapted to be automatically clutched with its corresponding clutch member responsive to and depending upon the direction of the rotation of the motor, brake 65 apparatus comprising an electromagnet car-

ried at the opposite end of the frame from the motor, means rotated with the rolls, and coöoperating brake members actuated by the magnet to engage said rotated members to positively arrest the rotation of the rolls, 70 and manually operated switches for starting and reversing the motor and for controlling the brake magnet.

8. A display apparatus having in combination movable display means, an electric 75 motor and its circuit for operating the same, contacts and a hand-actuated device for closing same to energize the motor at the will of the operator, and a second set of contacts and means operated responsive to the movement of the display means for actuating said last contacts to cause a continued energization of the motor after said hand-actuated device has been released. 80

9. A display apparatus having in combination movable display means, an electric motor and its circuit for operating the same, contacts and a hand-actuated device for closing same to energize the motor at the will of the operator, a second set of contacts, and a 90 contact-operating member operated responsive to the movement of the display means for actuating said last contacts to cause a continued energization of the motor after said hand-actuated device has been released, 95 and means for automatically returning said last contact-operating member to normal position to deenergize the motor when the display member has moved a predetermined distance. 100

10. A display apparatus having in combination movable display means comprising a movable sheet and two rolls upon which it is wound back and forth, an electric motor and its circuit for operating same, contacts 105 for closing the motor circuit to energize the motor, a second set of contacts for controlling the motor, and means controlling said contacts operated responsive to the movements of the sheet for actuating said last contacts to cause continued energization of the motor, said last contact-operating means comprising a finger pivoted near the sheet and operatively engaged by the same to be moved to close said last mentioned contacts, 110 and having coöoperating holes in the sheet which when they register with the finger permit the finger to return to its normal position to open the contacts, and means for returning said finger to normal position 120 when it registers with said holes. 115

11. A display apparatus having in combination movable display means comprising a movable sheet and two rolls upon which it is wound back and forth, an electric motor 125 and its circuit for operating same, contacts and a hand-actuated device for closing same to energize the motor at the will of the operator, a second set of contacts, and means controlling said contacts operated respon- 130

sive to the movements of the sheet for actuating said last contacts to cause continued energization of the motor after said hand-actuated device has been released, said 5 last contact-operating means comprising a finger pivoted near the sheet and operatively engaged by the same to be moved to close said last mentioned contacts, and having coöperating holes in the sheet which 10 when they register with the finger permit the finger to return to its normal position to open the contacts, means for returning said finger to normal position when it registers with said holes, and a guard plate on the 15 opposite side of the sheet from the finger and coöperating therewith to hold the sheet in proper alinement against the finger.

12. A display apparatus having in combination two rolls, display means adapted 20 to be wound upon and unwound from said rolls respectively, a motor for driving both rolls, two clutches for connecting the motor to the rolls, one for driving one roll from the motor and the other for 25 driving the other roll from the motor, a member of each clutch being geared to the motor to be rotated thereby and each adapted to coöperate with its corresponding clutch member so that the motor is automatically 30 clutched to one roll or the other depending upon the direction of rotation of the motor, means for suddenly and definitely stopping the rotation of the rolls when the power is cut off from the motor, said means comprising two members connected respectively with the roll shafts, and electromagnetically controlled coöperating means for 35 engaging said first two members to arrest the rotation of the rolls, a manually controlled switch for starting the motor and effecting the release of said arresting means, and contacts controlled responsive to a pre-determined movement of the display means for deënergizing the motor and for causing 40 the electromagnetically controlled arresting means to arrest the rotation of the rolls.

13. A display apparatus having in combination two rolls, display means adapted to be wound upon and unwound from said rolls 50 respectively, means for driving said rolls comprising a motor geared to one of said rolls, said gearing including a yieldable driving connection between said roll and the motor to protect the motor from sudden 55 stoppage of the roll, means for suddenly and definitely stopping the rotation of the roll when the motor is deënergized, said means comprising a member connected with said roll shaft and electromagnetically controlled 60 coöperating means for engaging said first member to arrest the rotation of said roll, a switch for starting the motor and effecting the release of said arresting means, and contacts controlled responsive to a predetermined movement of the display means for 65

deënergizing the motor and for causing the electromagnetically controlled arresting means to arrest the rotation of said roll.

14. A display apparatus having in combination movable display means and two rolls 70 upon which it is wound back and forth, an electric motor and its circuit for operating the same, electromagnetically controlled means operatively related to the driven roll for suddenly and definitely stopping the 75 same when the motor is deënergized, contacts and a manually-actuated device for closing the same to energize the motor and release the stopping means at the will of the operator, and a second set of contacts 80 controlled responsive to movement of the display means to cause a continued energization of the motor and continued release of the electromagnetically controlled stopping means after said manually-actuated device 85 has been released.

15. A display apparatus having in combination two rolls, a display means adapted to be wound upon and unwound from said rolls respectively, means for driving the rolls 90 comprising a motor and a yieldable driving connection such as to permit rotation of the motor when the rotation of the driven roll is suddenly arrested, electromagnetically controlled means for positively stopping 95 the rotation of the driven roll, said means comprising a toothed member connected with the roll, a locking finger operatively related thereto and an electromagnet for controlling the same, the teeth on said toothed member being sufficient in number 100 so that the movement of the display means will be arrested immediately that the locking finger is thrown, to prevent overrunning, and contacts controlling said motor and 105 electromagnet and controlled responsive to a predetermined movement of the display means to cut off the motive power and cause the locking finger to arrest the rotation of said driven roll.

16. A display apparatus having in combination movable display means, an electric motor and its circuit for operating the same, contacts adapted to be momentarily closed to energize the motor circuit, a second set 115 of contacts, and means operated responsive to the movement of the display means for actuating said last contacts to cause a continued energization of the motor after said first contacts have been opened, said second 120 set of contacts also being adapted to be actuated responsive to a predetermined movement of the display means for deënergizing the motor circuit.

17. A display apparatus having in combination two rolls, display means adapted to be wound upon and unwound from said rolls respectively, means for driving the display means comprising a motor and a yieldable driving connection between said motor 125 130

and display means such as to permit rotation of the motor when the display means has been suddenly arrested, electromagnetically controlled means including a rotatable member and a coöperating arresting member for suddenly and definitely stopping the travel of the display means, a switch for starting the motor and effecting disengagement of the stopping means, and 10 contacts controlled responsive to a prede-

termined movement of the display means for deenergizing the motor and for causing the electromagnetically controlled arresting means to arrest the movement of the display means.

15

In testimony whereof, we have signed our names to this specification.

CHARLES C. JAMES.
GEORGE C. JAMES.
